United States Patent Office

Des. 212,169
Patented Sept. 3, 1968

212,169

HASP

Daniel J. Foote, Wauwatosa, Wis., assignor to Master
Lock Company, Milwaukee, Wis., a corporation of
Wisconsin

Filed Jan. 12, 1968, Ser. No. 10,149

Term of patent 14 years

(Cl. D50—5)

FIG. 1

FIG. 2

FIG. 3

FIG. 4

FIG. 5

FIG - 6

FIG. 1 is a plan view of a hasp showing the design;
FIG. 2 is a bottom view thereof;
FIG. 3 is a front edge view of the hasp;
FIG. 4 is a left end view thereof on an enlarged scale;
FIG. 5 is a view of the opposite end of the hasp; and
FIG. 6 is a right end and side perspective view of the inverted hasp of FIG. 2 with the leaf in partially open position.

I claim:

The ornamental design for a hasp, as shown and described.
